UNITED STATES PATENT OFFICE

148,311

DESIGN FOR A VACUUM CLEANER

Howard C. Lilly, Sharon, Mass., assignor to
Masury-Young Company, Charlestown, Mass.,
a corporation of Massachusetts

Application May 20, 1947, Serial No. 139,163

Term of patent 14 years

(Cl. D9—2)

To all whom it may concern:

Be it known that I, Howard C. Lilly, a citizen of the United States, residing at Sharon, in the county of Norfolk and State of Massachusetts, have invented a new, original, and ornamental Design for Vacuum Cleaner, of which the following is a specification, reference being had to the accompanying drawing, forming part thereof.

Figure 1 is a side elevation of a vacuum cleaner showing my new design, and

Figures 2 and 3 are respectively top and bottom plan views thereof.

I claim:

The ornamental design for a vacuum cleaner, substantially as shown.

HOWARD C. LILLY.
